UNITED STATES PATENT OFFICE.

GEORGE T. TRUNDEL, JR., OF CLEVELAND, OHIO, ASSIGNOR TO THE AMERICAN MULTIGRAPH COMPANY, OF CLEVELAND, OHIO, A CORPORATION OF OHIO.

COLUMN-RULE.

1,109,375.

Specification of Letters Patent.

Patented Sept. 1, 1914.

Application filed June 18, 1914. Serial No. 845,756.

To all whom it may concern:

Be it known that I, GEORGE T. TRUNDEL, Jr., a citizen of the United States, residing at Cleveland, in the county of Cuyahoga and 5 State of Ohio, have invented a certain new and useful Improvement in Column-Rules, of which the following is a full, clear, and exact description, reference being had to the accompanying drawings.

10 The object of this invention is to provide a very simple, easily applied and effective column ruling device for use on a segmental, drum-like holder having parallel longitudinal rails. Such a holder, for example, 15 is illustrated by the drum of a Multigraph where the rails have undercut channels and are adapted to loosely confine parallel lines of type grooved on their opposite sides.

My ruling device is well adapted for 20 mounting on the Multigraph drum between type thereon, and it is so made that it may be put in place after the type is on the drum, and, when in place, is held against dropping out of the drum by its coaction with the 25 rails and against longitudinal shifting on the drum by abutting the type held thereon.

My rule comprises a thin flexible arcual strip having on its inner edge radially projecting teeth which lie in the same plane 30 with the strip and are free from any overhang or flanging on the lower parts of the teeth. By this means my rule may be put in place from the outside of a Multigraph drum or segment, either when the drum is empty 35 or between separated type thereon, by slightly twisting or warping the rule to allow the successive teeth to pass into the channels. When in place the rule stands normal to the drum,—that is, in the plane of a circular 40 section and it retains itself thereon by reason of the fact that it extends for a great enough arc so that teeth (all projecting toward the center) converge across the heads of the rails, preventing the rule dropping 45 out. The flexibility of the rule is an essential characteristic, as, without such flexibility it is impossible to put the rule in place between type already on the drum; that is to say, an inflexible rule having straight 50 edged radial teeth either could not be put on the drum from the outside, or, if put on the drum, would not hold itself against dropping off as the drum rotates. The characteristic that my rule may be put in place 55 from the side of the drum is of great impor-

tance, as it avoids the necessity of sliding the rule in endwise as the form is being made up. Rules which underhang the rails and slide in endwise may be effective to print, but trouble and delay is encountered in making corrections in the form set up. Furthermore, there is considerable delay in setting up each column of type and taking a proof of it before a rule is put in place. With my rules the whole form is set up as usual without the rules and then the type matter is separated at the desired arcual line for a short distance and the rule is warped into place. Then the type are shoved snugly against the rule or rules and locked with 60 clips in the usual manner and an effective printing form is provided. Another valuable characteristic of my rule is that, because of its thinness and absence of any lateral flanges, the type may be set snugly against 65 it, thus avoiding any waste of space between the type matter and the ruled lines in the printed form.

My invention is hereinafter more fully described and its essential characteristics are, 70 set out in the claims.

In the drawings, Figure 1 is a side elevation of one of my rules, the broken lines in this figure illustrating the radial character of the teeth; Fig. 2 is a perspective view of a portion of a Multigraph drum showing some 75 of my rules mounted thereon and showing one rule in the process of being put in place. The thickness of the rule is exaggerated in this figure for clearness of perspective illustration; Fig. 3 is an enlarged cross section of the rule held between adjacent type on an overhanging rail, such as employed in the Multigraph drum; Fig. 4 is a similar view 80 showing two rules spaced by a spreader to print adjacent parallel lines; Fig. 5 is a 85 diagrammatic elevation illustrating the rotary character of the drum.

As shown in Fig. 2, 10 indicates the body 90 of a Multigraph drum or segment, and 11 a series of L-shaped rails set into the drum and extending longitudinally thereof and equidistant from each other. This is a usual form of Multigraph drum or segment, as illustrated, for example, in Patents Nos. 105 1,052,910 and 1,094,065.

20, in Figs. 2, 3 and 4, indicate the type which have grooves 21 on their opposite sides to engage the heads 12 of the rails. The feet 22 of the type below the grooves 110

occupy the undercut or enlarged channels provided by the grooves 13 of the rails. This type, for example, may be of the form shown in Patent No. 836,026.

5 As illustrated in Fig. 5, the drum or segment with its type may be a rotary structure mounted on a shaft 15 and coacting with a roller platen 16, thus constituting a rotary printing couple, as usual in the Multigraph.

10 30, in each of the figures, indicates my column rule. This is a thin flexible arcual strip lying in a circular plane and having projecting radially from its inner edge teeth 31. I obtain perfectly satisfactory results 15 by making the edges of these teeth perfectly radial, which is the most convenient form of manufacture. It should be noted, however, that the variation of any particular teeth from a parallel edged tooth is very 20 slight. Accordingly, the teeth may be described as radial teeth having substantially parallel edges.

The body portion of my rule is substantially the same height as the heads of the 25 type, so that, when in place, the rule stands on edge on the surface of the drum or segment and its outer edge is in substantially the same cylindrical envelop as the printing face of the type. Owing to the comparatively sharp printing edge of the rule 30 it may be desirable, where a soft platen is employed, to raise its face a thousandth of an inch more or less above the face of the type to give an absolutely uniform impression, but this is a refinement which may 35 be ignored. The circumferential distance across the teeth of the rule is only slightly less than the distance between the rail heads. Accordingly, it would be impossible to shove

40 such a rule of any considerable length by a straight-line movement into position from the side of the drum, but experience demonstrates that it is a very simple matter to successively warp the rule, allowing one 45 tooth after another to enter its channel. As the rule comes into the upright position the radial direction of the teeth causes the edges thereof to engage the substantially radial faces of the rail heads, which holds the 50 rule effectively from dropping off of the drum as it rotates.

55 My rule may conveniently be made of ordinary sheet brass, which is hard enough so that kinks do not form in the rule during its flexure.

60 As heretofore stated, the rules shown in Fig. 2 are somewhat exaggerated in the thickness to enable them to be clearly shown in perspective. The thickness, however, varies with the width of the line which it is desired to print. That is to say, the rule may be very thin and print a very thin line, or it may be somewhat thicker to print a heavy line. To print two adjacent parallel 65 lines it is convenient to mount two thin

rules side by side but separated by a spacer made similar to a rule but not of printing height. Such spacer is shown at 32 in Fig. 4 and its radial teeth are indicated at 33.

I have referred to the rule being held 70 in place against lateral shifting on the drum by the abutting type, and this is a very convenient arrangement where it is desired to print type matter separated by column lines. For printing blank forms, however, the rules 75 may be held against lateral shifting by quads, which are locked in place, or by spring clips occupying the channels and directly abutting the rules. Two of such clips are shown by way of illustration at 40, in 80 Fig. 2, and may be considered as constructed in accordance with Patent No. 1,041,447.

Having thus described my invention, what I claim is:—

1. A column rule comprising a thin flexible arcual strip adapted to stand on edge and having radially projecting teeth on its inner edge which do not overhang in an arcual direction. 85

2. A column rule comprising a flexible arcual strip lying in one plane and having inwardly projecting teeth which lie in the said plane and do not project in an arcual direction. 90

3. A column rule consisting of a flexible arcual strip having substantially parallel edged teeth projecting radially from its inner edge. 95

4. A column rule consisting of a flexible arcual strip higher in a radial direction than 100 it is wide and having on its inner edge equidistant teeth projecting toward the center of the arc and having edges which do not overhang. 105

5. The combination, with a segmental or 105 drum-like holder having parallel rails, of a flexible arcual strip adapted to rest on said holder and having inwardly projecting radial teeth adapted to be forced directly from the side of the periphery of the holder into 110 the space between the rails.

6. The combination, with a drum-like type-holder having equi-distant parallel rails, of a column rule comprising a flexible arcual strip having on its inner edge teeth, the 115 arcual dimension of which is no greater throughout the length of the tooth than the distance between rails.

7. The combination, with a curved type-holder having parallel longitudinal rails 120 with overhanging edges, type grooved on its opposite sides mounted between said rails, and a flexible arcual strip mounted on the typeholder between the type thereon and resting on the outer surface of the rails and 125 having teeth which project inwardly between the heads of the rails but do not extend beneath such heads.

8. The combination, with a drum-like type-holder having parallel rails arranged longi- 130

tudinally on its periphery, of a column rule comprising a flexible arcual strip having teeth projecting inwardly from its concave edge, said rule extending for such distance 5 that the teeth while not engaging beneath the heads of the rails hold the rule in place by reason of engaging sides of distant heads which stand in converging planes.

9. The combination, with grooved type and 10 a curved holder therefor having longitudinal overhanging rails, of a flexible arcual column rule adapted to be mounted on the face of such holder between type in lines, and teeth no wider than the distance between the 15 rail heads and extending from the supporting edge of the strip and spaced to enter channels which the type lines occupy.

10. In a duplicating machine, the combination, with a rotary printing drum having 20 a plurality of undercut channels on its periphery, of type grooved in its opposite sides and fitted in said channels, and a flexible rule strip having a printing surface curved in concentric relation with said drum 25 and held between said type thereon and having teeth occupying the intermediate portions of the channels but not extending into undercut portions thereof.

11. The combination of a drum-like type- 30 holder having a plurality of parallel undercut channels in its periphery, type occupying said channels and having projecting feet adapted to fit in the undercut portions of the channels, and a flexible rule strip having a 35 printing surface curved in concentric relation with said drum-like typeholder and having inwardly projecting tongues which are no wider than the throat of the channels, whereby the rule may be inserted between 40 type matter pre-existing on the drum.

12. In a duplicating machine, the combination of a rotary printing drum having a plurality of undercut channels on its periphery, of type occupying said channels and 45 extending into the undercut portions thereof, and a thin laterally-flexible rule strip having a printing surface curved in concentric relation with said drum and held against shifting along the drum by means of such 50 type abutting its opposite sides, said strip

having radially projecting teeth occupying said channels but not extending arcually into the undercut portions of the channels, whereby the rule may be put in place directly from the side of the drum while type 55 matter is on the drum on each side of the rule.

13. In a duplicating machine, the combination, with a rotary printing drum having a plurality of undercut channels in its periphery, of type having projecting feet and loosely held in said channels, and a flexible rule strip having a printing surface curved in concentric relation with said drum and having teeth projecting radially from its 60 concave edge and no wider than the throat to said channels, whereby said rule may be put in place between pre-existing columns of type matter on the drum and when in place the radial projection of the teeth hold the 65 rule to the drum independently of the type matter.

14. The combination of a drum-like type- 70 holder consisting of a body having mounted thereon parallel rails with overhanging 75 heads having substantially radial faces, type grooved on their opposite sides and adapted to occupy the channels between adjacent rails and have their feet extend into the grooves of the rails, and a flexible arcual 80 rule strip having a printing surface curved in concentric relation with the drum-like holder and having inwardly projecting teeth with substantially radial edges, said teeth being of slightly less circumferential 85 dimension than the distance between the heads of the rails, whereby the rule may be inserted between type matter pre-existing on the holder by flexing the rule but when in place will be held by the convergence of the 90 substantially radial teeth which engage the substantially radial faces of some of the rail heads.

In testimony whereof, I hereunto affix my signature in the presence of two witnesses. 95
